UNITED STATES PATENT OFFICE.

JOHN EINSFIELD, OF ONEIDA, NEW YORK, ASSIGNOR TO CHAPPELL, CHASE, MAXWELL & CO., OF SAME PLACE.

DESIGN FOR A BURIAL-CASKET.

SPECIFICATION forming part of Design No. 12,588, dated December 6, 1881.

Application filed July 23, 1881. Term of patent 7 years.

To all whom it may concern:

Be it known that I, JOHN EINSFIELD, of Oneida, in the county of Madison, in the State of New York, have invented new and useful 5 Improvements in Designs for Burial-Caskets, of which the following, taken in connection with the accompanying drawings, is a full, clear, and exact description.

The nature of this design consists in the embellishment of a burial-casket by a semi-columnar molding faced with cloth, satin, or any suitable textile fabric, and presenting at its convex side oblique or spiral ribs or corrugations, with a cord lying in the indented or depressed portions thereof, substantially as herein-after more fully described, and specifically set forth in the claim.

In the annexed drawings, Figure 1 represents a side view of a burial-casket ornamented with 20 my design. Fig. 2 is a top view of the same. Fig. 3 is an enlarged detached view of the molding, and Fig. 4 is a transverse section on line *xx*.

Similar letters of reference indicate corresponding parts.

A represents a molding of semicircular or segmental form in cross-section. The convex side thereof is ribbed or corrugated obliquely or spirally, the ribs or corrugations projecting 25 over the edges of the molding, and being covered with cloth or textile fabric *a*, of any desired or suitable material, thereby presenting a semi-columnar spiral similar to the form of the longitudinal half of a rope of extra fine material and finish. I still further ornament the aforesaid molding by laying into the indented

or depressed portions of the convex face a cord, *b*, as shown in Fig. 3 of the drawings.

The described molding is applied with its flat face to the burial-casket, and can, like other 40 moldings, be disposed in any desirable manner to harmonize with other trimmings and suit the taste generally. It also furnishes a beautiful trimming for the usual name-plate, *F*, on top of the casket, as shown in the drawings. 45

I am aware that rounded moldings have been made with ribs on their convex side; but said ribs usually terminated in straight and smooth edges at the junction of the convex side with the flat back of the molding, and therefore deprived said molding of the beautiful effect attained in my design, which resembles a longitudinal section of a twisted rope. Hence I do not claim, broadly, a diagonally-corrugated molding; but 55

What I do claim is—

As an ornamentation of burial-caskets, a semi-columnar molding faced with cloth, satin, or any suitable textile fabric, and presenting at its convex side oblique or spiral ribs or corrugations, with a cord lying in the indented or depressed portions thereof, substantially as 60 specified and shown.

In testimony whereof I have hereunto signed my name and affixed my seal, in the presence 65 of two attesting witnesses, at Oneida, in the county of Madison, in the State of New York, this 22d day of June, 1881.

JOHN EINSFIELD. [L. S.]
